ELECTRIC DISCHARGE DEVICE AND ELECTRODE ASSEMBLY THEREFOR

William S. Brian, Owensboro, Ky., assignor to
General Electric Company, a corporation of
New York

Application June 15, 1945, Serial No. 599,712

15 Claims. (Cl. 250—27.5)

1

My invention relates to improved electric discharge devices and particularly to an improved unitary electrode assembly and mounting therefor. The invention is in the nature of an improvement on the discharge devices described and claimed in my copending patent application Serial No. 557,126, filed October 4, 1944, and assigned to the assignee of the present invention.

It is an object of my invention to provide a new and improved unitary electrode assembly adapted to be manufactured with a minimum of hand labor.

It is another object of my invention to provide a new and improved unitary electrode assembly which is rugged and not readily damaged during assembly or while it is carried in inventory as a component part.

It is still another object of my invention to provide a new and improved mounting for a unitary electrode assembly.

It is a still further object of my invention to provide an improved electric discharge device in which a high degree of accuracy in the spacing of electrodes is insured while at the same time the labor required for assembly is reduced.

My invention will be better understood by reference to the following description taken in connection with the accompanying drawing, and its scope will be pointed out in the appended claims. In the drawing, Fig. 1 is an elevational view, partly in section, of an electric discharge device embodying my invention; Fig. 2 is a sectional view taken along the line 2—2 of Fig. 1; Fig. 2a is a perspective view of the electrode assembly support of the device of Figs. 1 and 2; Fig. 3 is an elevational view, in section, of the unitary electrode assembly employed in the device of Figs. 1 and 2; and Figs. 4 and 5 are detail views showing a modified cathode structure.

Referring now to the drawing, the device includes a circular metal header 1 having a plurality of openings arranged about a central positioning hub 2 for the reception of rigid lead-in conductors 3, each of which is sealed to the header by a body of glass 4. The lead-in conductors 3 are connected at their upper ends with the various electrodes of a unitary electrode assembly designated generally by the numeral 5. As illustrated clearly in Fig. 3, the electrode assembly includes an open-ended generally cylindrical or cup-shaped retaining member 6 having an end wall 7 joined to side wall portions 8 and 9 which terminate at their upper ends in flanges 10. The electrode assembly includes a plurality of spacer members 11—15, inclusive, which are preferably

2

annular in shape and formed of suitable insulating material such as steatite or an alumina-silica-magnesia compound of the type commercially known as Alsamig. The spacers are preferably accurately ground or lapped to the desired thickness to accurately determine the relative spacing of the various electrodes. As indicated in the drawing, an anode having a planar central portion 16 is provided with a marginal portion 17 received between spacers 11 and 12. An indirectly heated wafer-like thermionic cathode is provided by a pair of sheet metal members 18 and 19 which are joined together to form a cylindrical enclosure within which a heater element, including lead-in wires 20 and 21, is positioned. As indicated clearly in Fig. 2, the cathode is provided with outwardly extending tabs 22 which are received between the spacers 12 and 13. The spacers 12 and 13 differ from the remaining spacers in that they each include an inwardly extending flange 23 which substantially closes off the area around the cathode. These members are also provided with a recess 24 to receive the current supply conductors 20 and 21 of the cathode heater. As will be readily appreciated by those skilled in the art, the opposite exterior surfaces of the cathode are preferably coated with an electron emission enhancing material such as a compound containing one or more of the alkaline earth oxides. A control member or grid having a central portion of wire or mesh 25 is provided with an outwardly extending marginal flange 26 which is received between the spacers 13 and 14. A second anode or plate electrode 27 of the same construction as the anode 16 is provided with a marginal portion 28 which is received between the spacers 14 and 15. As illustrated in the drawing, the side walls of the member 6 are preferably substantially the full height of the stack including the electrodes and spacers so that there is provided a suitable retainer into which the parts may be dispensed at the different stations of an automatic machine. When the electrodes and spacers are in position with the lower spacer resting on the end wall of the member 6 the unitary assembly is completed by a retaining cap 29 having a central wall portion 30 engaging the upper spacer 15 and an outwardly extending flange 31 which is welded or otherwise bonded to the flange 10 of the retainer 6. The dimensions of the various parts are preferably chosen so that after positioning of the parts and prior to the bonding operation, the flanges are slightly separated. In this manner, the bonding operation is effective to apply pres-

sure to the electrode stack and insure accurate electrode spacing in accordance with the dimensions of the punchings forming the electrodes and the thickness of the spacing rings. In order to provide the desired resilience in the retaining structure, outwardly projecting annular ribs 32 and 33 are provided between the end wall and flange portions of the retaining cap and the retaining member 6, respectively. This structure accommodates all expansion that occurs during operation and firmly retains the electrodes and spacers in assembled relation. The wall portions 8 and 9 of the cup-like retaining member 6 are provided with extensions shown in Fig. 1 and designated by numerals 34 and 35 which are free of the retainer at both ends so that they may resiliently engage the spacers and restrain them from lateral movement. As clearly shown in Fig. 2, these extensions are curved inwardly toward the spacers. The unitary assembly 5 is supported from a flange 36 on the header 1 by a sheet metal support including a circular flange 37 which registers with the flange 36 and a pair of diametrically opposed vertical supports 38 and 39 which terminate at their upper ends in inwardly directed flanges 40 and 41, respectively. The flanges 40 and 41 are bonded, as by welding, to the flanges of the retaining members of the electrode assembly. As illustrated in Figs. 1 and 2, a suitable getter strip 47 may be connected between one of the lead-in conductors 3 and the arm 38 of the sheet metal support. The envelope of the discharge device includes a sheet metal can-like member 48 having an outwardly extending flange surrounding the open end thereof and registering with the flanges 36 and 37. The unitary electrode assembly and mounting described above provide a support which is entirely independent of the lead-in conductors.

In assembling the discharge device described above, the unitary electrode assembly is welded to the support including the arms 38 and 39. The support is then positioned on the header with flange 37 of the support registering with flange 36. The connections between the various electrodes and the lead-in conductors are then made and the assembly completed by placing the envelope 48 in position with the flange 49 registering with the flange 37. The three flanges are preferably welded together in one operation. The tube may be exhausted before the welding operation through the space between the flanges 36 and 49 or, if desired, exhaust of the device may be accomplished through a suitable tubulation (not shown).

In some applications it is desirable to operate the cathodes of the different discharge paths of a duplex discharge device at different voltages. In such a case it will be apparent that two independent cathode structures may be supported in spaced and insulated relation in the assembly. In Figs. 4 and 5 I have illustrated a modified cathode structure in which two mutually insulated cathode spacers are heated by a single heater element. Referring to the drawing, a heater element including a coil of insulated wire 50 is supported in an insulating spacer 51 having a suitable recess 52 for receiving the terminal conductors 53 and 54 of the heater element. Positioned on opposite sides of the spacer 51 are cathode disks 55 and 56 which are preferably coated with an electron emission enhancing material. Each of these disks is provided with a plurality of supporting portions in the form of wires 57, 58 and 59 which are bonded to the

disks and extend radially therefrom. As illustrated in Fig. 4, these supports are received in suitable recesses 60 formed in the spacer 51. The wires 59 are preferably longer than the supporting wires 57 and 58 and provide suitable terminals for connecting the cathode members with the lead-in conductors of the device. The spacer 51 is provided with a plurality of openings 61 in the region surrounding the cathode disks 55 and 56 to minimize the transfer of heat from the cathode to the supporting structure.

In Fig. 5, the spacer 51 and cathode elements 55 and 56 are shown assembled between a pair of spacer elements 62 and 63. In order to prevent the cathode disk from buckling under operating conditions, it may be desirable to bend the supporting wires out of the plane of the disk, so that the subsequent bending of these supporting portions into the plane of the disk, upon assembly between the spacers, is effective to stress the cathode disks. It will be understood that the assembly shown in Fig. 5 occupies generally the space occupied by the cathode 18-19 and spacer elements 12 and 13 as shown in Fig. 3.

It is apparent from the foregoing description of the illustrated embodiment of my invention that a very simple and rugged unitary electrode assembly is provided which is particularly well adapted for manufacture on automatic machinery. The insulating spacers and electrodes may be alternately dispensed into the retaining member 6 and the assembly completed by welding the flange of the cover member and the flange of the retainer 6. This construction avoids the time consuming assembly step of threading the support wires through the insulating spacers which is present in the manufacture of practically all conventional receiving type tubes. The invention provides a structure which makes possible this saving of labor and at the same time results in a more compact and accurately constructed device so that the tube characteristics are more uniform and more readily reproduced. The support of this assembly is also simple and rugged while at the same time providing ready access to the lead-in conductors for making the connections between the lead-in conductors and the various electrodes.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. An electrode assembly comprising a plurality of electrodes having generally planar active surfaces and marginal supporting portions, a plurality of spacers assembled in a stack with said marginal portions received between the various spacers to support said electrodes in mutually spaced and insulated relation, and a pair of metal retaining members positioned in engagement with the opposite ends of said stack, said retaining members having portions bonded together to form a unitary structure for holding said electrodes and spacers in assembled relation.

2. An electrode assembly comprising a plurality of electrodes including marginal supporting portions, a plurality of spacers assembled in a stack with said marginal portions received between the various spacers to support said elec-

trodes in mutually spaced and insulated relation, a cup-like metal structure adapted to receive and retain said stack of spacers and electrodes, and a retaining member engaging said stack at the end thereof adjacent the open end of said cup and joined to said cup-like structure to form a unitary electrode assembly.

3. An electrode assembly comprising a plurality of electrodes having generally planar active surfaces and marginal supporting portions, a plurality of spacer rings assembled in a stack with said marginal portions received between the various rings to support said electrodes in mutually spaced and insulated relation, a metal member having an end wall, and side wall portions substantially equal in height to the height of said stack, said stack being received in said member with one end thereof in engagement with said end wall, and a second metal member having a wall portion engaging the opposite end of said stack and a second portion bonded to said first metal member.

4. An electrode assembly comprising a plurality of electrodes having generally planar active surfaces and marginal supporting portions, a plurality of ring-like spacers of insulating material assembled in a stack with said marginal portions received between the various spacers to support said electrodes in mutually spaced and insulated relation, and a pair of metal retaining members positioned in engagement with the opposite ends of said stack, at least one of said retaining members having portions extending axially of said stack and mechanically connected to the other of said members to provide a unitary electrode assembly.

5. An electrode assembly comprising a plurality of electrodes having generally planar active surfaces and marginal supporting portions, a plurality of spacers assembled in a stack with said marginal portions received between the various spacers to support said electrodes in mutually spaced and insulated relation, a cup-like retaining structure engaging one end of said stack and including side wall portions extending axially along the outside of said stack and a retaining member engaging the other end of said stack, and means mechanically connecting said side wall portions to said retaining member.

6. An electrode assembly comprising a plurality of electrodes having central active portions and marginal supporting portions, a plurality of spacers of insulating material assembled in a stack with said marginal portions received between the various spacers to support said electrodes in mutually spaced and insulated relation and a pair of retaining members positioned in engagement with the opposite ends of said stack, means extending axially of and on the exterior of said stack and mechanically connecting said members together to provide a unitary electrode assembly, and at least one resilient section in the retaining structure provided by said last mentioned means and said pair of metal members.

7. An electrode assembly comprising a plurality of electrodes having generally planar active surfaces and marginal supporting portions, a plurality of ring-like spacers of insulating material assembled in a stack with said marginal portions received between the various spacers to support said electrodes in mutually spaced and insulated relation, and a pair of metal retaining members positioned in engagement with the opposite ends of said stack, at least one of said members having portions extending axially of said stack

and mechanically connected to the other of said members to provide a unitary electrode assembly and a resilient section formed in at least one of said members, said members being drawn into engagement with the opposite ends of said stack when said members are connected together to flex said resilient sections.

8. An electric discharge device including a header having an outwardly extending flange, a unitary electrode assembly including a retaining structure and a plurality of electrode elements and spacer rings mounted within said retaining structure, and a support for said electrode assembly including a flange resting on the flange of said header and upwardly extending portions joined to opposite sides of said retaining structure.

9. An electric discharge device including a header, a unitary electrode assembly including a metallic retaining structure and a plurality of electrode elements and spacer rings mounted within said metallic retaining structure, and a support for said electrode assembly including a portion resting on said header and upwardly extending portions joined to opposite sides of said retaining structure.

10. An electric discharge device comprising an envelope including a header, a plurality of lead-in conductors sealed through said header, a unitary electrode assembly including a retaining structure and a plurality of electrode elements and spacer rings mounted within said retaining structure, flexible connections between said lead-in conductors and the various electrodes, and a support for said electrode assembly including a portion resting on said header and upwardly extending portions engaging said retaining structure to support said assembly independently of said lead-in conductors.

11. An electric discharge device including a circular header having a plurality of lead-in conductors extending through said header and arranged in a circle, a unitary electrode assembly including a retaining structure and a plurality of planar electrode elements and spacer rings mounted within said retaining structure, and a support for said electrode assembly resting on said header outside of said circle and having upwardly extending portions joined to said retaining structure, said support and said retaining structure having openings in the side walls thereof to facilitate the making of connections between the lead-in conductors and the various electrodes of the assembly.

12. An electric discharge device including a header, a unitary electrode assembly including a metallic retaining structure having flange portions extending outwardly therefrom at points spaced around the outside of the assembly, and a supporting structure for said electrode assembly having one end positioned against said header and portions at the other end joined to said flange portions.

13. An electric discharge device including a header having an outwardly extending metal flange, a unitary electrode assembly including a metallic retaining structure having flange portions extending outwardly therefrom at points spaced around the outside of the assembly, and a supporting structure for said electrode assembly having a flange resting on the flange of said header and portions at the other end joined to the flanges on said retaining structure.

14. An electric discharge device including a header having an outwardly extending flange, a

unitary electrode assembly including a metal retaining structure, a support for said electrode assembly including a flanged portion registering with the flange of said header and arm portions joined with said retaining structure, and a metal envelope for said device including a flange registering with the flange of said support, the flanges of said header, support, and said envelope being bonded together.

15. An electric discharge device including a header having an outwardly extending metal flange, a unitary electrode assembly including a metal retaining structure, a metal support for said electrode assembly including a flanged portion registering with the flange of said header and

an upwardly extending portion joined with said retaining structure, and a metal envelope for said device including a metal flange registering with the flange of said support, the flanges of said header, support, and said envelope being bonded together.
